UNITED STATES PATENT OFFICE.

MICHAEL BECK, OF MINNEAPOLIS, MINNESOTA.

CARBURETER.

1,264,141.

Specification of Letters Patent. Patented Apr. 30, 1918.

Original application filed May 11, 1916, Serial No. 96,818. Divided and this application filed September 22, 1916. Serial No. 121,596.

To all whom it may concern:

Be it known that I, MICHAEL BECK, a citizen of United States, residing at Minneapolis, in the county of Hennepin and State 5 of Minnesota, have invented certain new and useful Improvements in Carbureters; and I do hereby declare the following to be a full, clear, and exact description of the invention, such as will enable others skilled in 10 the art to which it appertains to make and use the same.

My invention has for its object to provide an extremely simple and highly efficient carbureter, primarily for internal combustion 15 engines; and is a division of my co-pending application, entitled "Vapor generators and mixers", filed May 11, 1916, under S. N. 96,818.

To the above end, generally stated, the 20 invention consists of the novel devices and combinations of devices hereinafter described and defined in the claims.

In the accompanying drawings, which 25 illustrate the invention, like characters indicate like parts throughout the several views.

Referring to the drawings,

Figure 1 is a view of the improved carbureter in central vertical section; and

Fig. 2 is a fragmentary detail view in section taken principally on the irregular line 2—2 of Fig. 1.

The numeral 1 indicates a casing having a screw-threaded extension 2 adapted to be 35 screwed into the fuel intake manifold of an internal combustion engine, not shown. Formed in the casing 1, is a mixing chamber 3, which has communication with the said fuel intake manifold through the extension 40 2. In the bottom of the casing 1, is formed a gaseous fuel chamber 4, the top or crown 45 of which extends into the mixing chamber 3. The bottom of the fuel chamber 4 is open and has screwed therein the delivery end of a gaseous fuel conveying conduit 5, which leads from any suitable source of supply. In the top of the fuel chamber 4, is a port 6 and in the top of the casing 1, is a relatively large annular opening 7

50 axially alined with said port.

A cap 8 is screwed into the opening 7 and is provided with a hub 9 that is co-axial therewith. The lower end of the cap 8 has upwardly converging surfaces to afford a

valve seat 10. Within the top of the cap 8, 55 is formed a plurality of circumferentially spaced air intake ports 11. The walls of the port 6 upwardly converge to afford a seat for a fuel intake valve 12, normally closing said port and arranged to open into 60 the fuel chamber 4. The air intake ports 11 are normally closed by an air intake valve 13, mounted on the seat 10 and having a tubular stem 14 mounted in the hub 9 and extending thereabove. An adjustable abutment 15, in the form of a thumb-nut, has screw-threaded engagement with the upper end of the valve stem 14. A coiled spring 16 is compressed between the cap 8 and abutment 15 and yieldingly holds the valve 70 13 closed.

The fuel intake valve 12 is provided with a tubular stem 17, which is telescoped through the valve stem 14 and has on its upper end an adjustable abutment 18 in the 75 form of a thumb-nut having screw-threaded engagement therewith. A pair of opposing coiled springs 19 and 20 are compressed, respectively, between the valves 12 and 13 and abutments 15 and 18. These springs 80 19 and 20 are counterpoised under substantially the same tension, with a slight excess of tension in the spring 20. The stems of the valves 12 and 13 are held against rotary movement, the one within the other 85 and in the hub 9 by a screw pin 21 having screw-threaded engagement with said hub. The inner end of this pin 21 extends through a slot 22 in the valve stem 14 and into a groove 23 formed in the valve stem 17. 90 It is important to note that the screw pin 21, while holding the valve stems against rotary movement, permits independent endwise movements thereof.

Under the suction stroke of the engine, 95 the air intake valve 13 will open first, on account of its excess area, over the valve 12, and compress the spring 16. The spring 20, owing to its excess of tension over the spring 19, will hold the valve 12 closed, at 100 the time the valve 13 starts to open, but after said valve 13 has moved a slight distance and compressed the spring 19, said spring 19 and the spring 20 will neutralize and the valve 12 will be opened by the further movement of the valve 13. By thus 105 slightly opening the valve 13, before the valve 12 starts to open, insures a good sup-

ply of air to the mixing chamber with which the fuel charge commingles with the opening of the valve 12.

During the closing movement of the valves 12 and 13, the valve 12 will first be seated and then the valve 13. This final closing movement of the valve 13 will place the spring 20 under its excess counterpoised tension, which insures the proper seating of both of the valves. The tension of the springs 16 and 20 may be varied by the adjustment of the abutments 15 and 18. By adjusting the abutment 18 to place the spring 20 under a greater tension, will 15 automatically decrease the tension on the spring 19 and vice versa.

In starting the engine when the same is cold, gasoline or other light hydrocarbon liquid fuel is delivered directly into the 20 mixing chamber 3, through a pipe or conduit 24 leading from a suitable source of supply. This pipe 24 extends horizontally through the casing 1 into the fuel chamber 4 and its delivery end portion extends vertically upward into a socket 25 formed in the bottom of the fuel intake valve 12. Said socket 25 is of such depth as to permit the valve 12 to slide on the pipe 24, during its opening and closing movements. The 25 axial opening in the stem 17 of the valve 12 opens into the socket 25 and has communication with the mixing chamber 3, through oblique radial ports 26 formed in said valve 12.

35 The ports 26 may be opened and closed, at will, by a needle valve 27, the stem of which is mounted in the tubular stem 17 of the valve 12 and has screw-threaded engagement therewith at its upper end portion. A knurled finger piece 28 is secured to the upper end of the valve stem 27 by which said stem may be operated to open and close the needle valve. The passageway, through the extension 2 from the mixing chamber 3 to the fuel intake manifold of the engine, has mounted therein a butterfly valve 29, by which the gaseous fuel charge to the engine may be controlled. Any suitable means, not shown, may be provided for actuating the valve 29. To permit the bent delivery end portion of the pipe 24 to be inserted into the fuel chamber 4, a relatively large hole is made in the casing 1 and this hole is closed by a screw plug 30, through which the pipe 24 extends. 55

What I claim is:—

1. In a carbureter, the combination with a casing having an air intake port and a fuel intake port, of an air intake valve and a fuel intake valve coöperating respectively with said ports and normally closing the same, a spring yieldingly holding the air intake valve closed, and two opposing springs connecting the fuel intake valve to the air intake valve, one of said two springs

having a slight excess of tension over the other thereof, the initial opening movement of the air intake valve neutralizing said two springs and causing the fuel intake valve to move with the air intake valve. 70

2. In a carbureter, the combination with a casing having an air intake port and a fuel intake port, of an air intake valve and a fuel intake valve coöperating respectively with said ports and normally closing the same, said two valves having stems telescoped, the one through the other, abutments on the stems of said valves, a spring compressed between a relatively fixed support and the abutment on the outer valve stem, and a spring compressed between said two abutments. 75

3. In a carbureter, the combination with a casing having an air intake port and a fuel intake port, of an air intake valve and a fuel intake valve coöperating respectively with said ports and normally closing the same, said two valves having stems telescoped, the one through the other, adjustable abutments on the stems of said valves, a spring compressed between a relatively fixed support and the abutment on the outer valve stem, and a spring compressed between said two abutments. 80

4. In a carbureter, the combination with a casing having an air intake port and a fuel intake port, of an air intake valve and a fuel intake valve coöperating respectively with said ports and normally closing the same, said two valves having stems telescoped, the one through the other, abutments on the stems of said valves, a spring compressed between a relatively fixed support and the abutment on the outer valve stem, a spring compressed between said two abutments, and a spring compressed between said two valves. 95

5. In a carbureter, the combination with a casing having an air intake port and a fuel intake port, of an air intake valve and a fuel intake valve coöperating respectively with said ports and normally closing the same, said two valves having stems telescoped, the one through the other, adjustable abutments on the stems of said valves, a spring compressed between a relatively fixed support and the abutment on the outer valve stem, a spring compressed between said two abutments, and common means for holding the valve stems against rotation. 110

6. In a carbureter, the combination with a casing having an air intake port and a fuel intake port, of an air intake valve and a fuel intake valve coöperating respectively with said ports and normally closing the same, said two valves having stems telescoped, the one through the other, abutments on the stems of said valves, a pair of opposing springs, the one compressed between said two abutments and the other compressed be- 115 120 125 130

tween said two valves, and a spring compressed between a relatively fixed support and the abutment on the outer valve stem tending to close said two valves.

- 5 7. In a carbureter, the combination with a casing having an air intake port and a fuel intake port, of an air intake valve and a fuel intake valve, the former having a greater area than the latter, said valves coöperating respectively with said ports and normally closing the same, said two valves having stems telescoped, the one through the other, abutments on the stems of said valves, a pair of opposing springs, the one compressed between said two abutments and the other compressed between said two valves, the spring compressed between said two abutments having a slight excess of tension over the spring compressed between said two valves, and a spring compressed between a relatively fixed support and the abutment on the outer valve stem and tending to hold said two valves closed.

8. In a carbureter, the combination with a casing having an air intake port and a fuel intake port, of an air intake valve and a fuel intake valve, the former having a greater area than the latter, said valves coöperating respectively with said ports and normally closing the same, said two valves having stems telescoped, the latter through the former, abutments on the stems of said valves, a pair of opposing springs, the one compressed between said two abutments and the other between said two valves, the spring compressed between said two abutments having a slight excess of tension over the spring compressed between said two valves, and a spring compressed between a relatively fixed support and the abutment on the outer valve stem and tending to hold said two valves closed.

9. In a carbureter, the combination with a casing having a fuel intake port and a cap normally closing and opening in said casing and having a hub and an air intake port, of an air valve normally closing said air port and having a tubular stem extending through the hub of said cap, an abutment on

the stem of said valve, a spring compressed between said cap and abutment and tending to hold said valve closed, a fuel intake valve normally closing said fuel intake port and having a stem telescoped through the stem of the air intake valve, an abutment on the stem of the fuel intake valve, and a pair of opposing springs, the one compressed between said two abutments and the other between said two valves, the spring compressed between said two abutments having a slight excess of tension over the spring compressed between said two valves.

10. In a carbureter, the combination with a casing having a fuel intake port, of a fuel intake valve coöperating with said port, an auxiliary fuel supply conduit opening into said casing through said valve, and a valve carried by the fuel intake valve for controlling said auxiliary fuel supply conduit in all positions of said fuel intake valve.

11. In a carbureter, the combination with a casing having a fuel intake port, of a fuel intake valve coöperating with said port, an auxiliary fuel supply pipe with the delivery end of which said valve has telescopic movement, a port in said valve connecting the auxiliary fuel supply pipe with the interior of said casing, and a valve for controlling the port in said fuel intake valve in all positions of said fuel intake valve.

12. In a carbureter, the combination with a casing having a fuel intake port, of a fuel intake valve coöperating with said port and having a tubular stem, an auxiliary fuel supply pipe with the delivery end of which said valve has telescopic engagement, a port in said valve connecting the auxiliary fuel supply pipe with the interior of said casing, and a needle valve in the stem of said fuel intake valve for controlling the port therein in all positions of said fuel intake valve.

In testimony whereof I affix my signature in presence of two witnesses.

MICHAEL BECK.
